(57) **CLAIM**

The ornamental design for an animal shaped toy with an audio device, as shown and described.

DESCRIPTION

FIG. 1 is a perspective top front view of an animal shaped toy with an audio device, showing my new design;

FIG. 2 is a perspective top rear view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

The broken lines represent a boundary area for a tail and facial features for an animal shaped toy with audio device and do not form any part of the claimed design.
